(57) **CLAIM**

The ornamental design for a light guide, as shown and described.

DESCRIPTION

A portion of the material in this patent document is subject to copyright protection under the copyright laws of the United States and of other countries. The owner of the copyright rights has no objection to the facsimile reproduction by anyone of the patent document or the patent disclosure, as it appears in the United States Patent and Trademark Office publicly available file or records, but otherwise reserves all copyright rights whatsoever. The copyright owner does not hereby waive any of its rights to have this patent document maintained in secrecy, including without limitation its rights pursuant to 37 C.F.R. § 1.14.

FIG. 1 is a front, top and right side perspective view of a first embodiment of an edge-lit light guide showing my new design;

FIG. 2 is a top view thereof;

FIG. 3 is a front view thereof;

FIG. 4 is a rear view thereof;

FIG. 5 is a right side view thereof, the left side being a mirror image thereof;

FIG. 6 is a front, top and right side perspective view of a second embodiment thereof;

FIG. 7 is a top view thereof;

FIG. 8 is a front view thereof;

FIG. 9 is a rear view thereof; and,

FIG. 10 is a right side view thereof, the left side being a mirror image thereof.

The broken lines represent the bounds of the claim, but form no part of the claimed design.

1 Claim, 4 Drawing Sheets
